SELF STARTING GASEOUS ELECTRIC
DISCHARGE DEVICETed E. Foulke, Nutley, N. J., assignor to General
Electric Vapor Lamp Company, Hoboken, N. J.,
a corporation of New Jersey

Application July 1, 1932, Serial No. 620,515

7 Claims. (Cl. 176—124)

The present invention relates to gaseous electric discharge devices generally, and more particularly to discharge devices operating with a long positive column discharge.

5 A particular object of the invention is to provide a gaseous electric discharge device of the positive column type in which a discharge may be initiated by the application of a potential of less than 110 volts D. C. between the electrodes thereof. A further object of my invention is to provide a novel method of operating an electric discharge device. Another object of my invention is to provide a novel method of forming a coating of low work function. Still other objects and advantages 10 of the invention will appear from the following detailed description thereof, or from an inspection of the accompanying drawings.

The invention consists in a new and novel electric gaseous discharge device, and in a novel method of production and of operation thereof, 20 as hereinafter set forth and claimed.

It is well known that electric gaseous discharge tubes in their normal un-ionized state offer a very considerable resistance to the passage of an electric discharge therethrough, it being necessary to ionize the gas or vapor before a positive column discharge can take place therethrough at low voltage. To attain this ionization it is obviously necessary to provide means for producing ions at 25 a rate which exceeds the loss of ions through recombination with electrons in space and at the walls of the device. In the past this has involved either the application of an extremely high potential to produce the required ionization, or the production of ions by means of a discharge to an auxiliary electrode across a gap which is sufficiently short to permit the initiation of a discharge at the line potential. The first expedient is obviously undesirable, since it involves the use 30 of auxiliary apparatus such as a high voltage transformer of poor regulation or the equivalent thereof; or a high frequency, high voltage mechanism such as a Shelton coil; or means to produce an inductive surge of the required potential. Hence the use of the auxiliary discharge, avoiding as it does the use of auxiliary apparatus, has 35 theoretically been the more desirable of these expedients. In practice, however, it has been found impossible to start positive column discharges of any appreciable length on the usual commercial circuits having potentials of the order of 110 volts A. C. or D. C., for the reason that the auxiliary discharge has been localized at the end of the tube, diffusion of the ions alone being relied upon to reduce the potential required to

initiate the positive column in the tube. This diffusion, however, falls off rapidly with the distance, the number of ions which reach a distance of but three tube diameters from the discharge being insignificant. Thus this method has required the use of potentials of the order of 220 volts or more, except where the length of the positive column was less than three tube diameters. This mode of ionizing the gas has, therefore, never gone into commercial use due to the 10 obvious limitations inherent therein.

I have now discovered that by means of a novel arrangement of an electrically conducting body within the discharge device the auxiliary discharge may be made to travel along the tube, 15 with the result that the entire discharge path is ionized with but little dependence upon diffusion of the ions from the auxiliary discharge. In some cases this electrically conducting body may be electrically isolated from the electrodes; in other 20 cases it constitutes an auxiliary electrode of novel shape and disposition. But in either case a glow discharge is produced at potentials of 110 volts or less, this glow being caused to spread throughout the length of the tube with the resulting 25 ionization of the discharge path.

For the purpose of illustrating my invention I have shown several embodiments thereof in the accompanying drawings, in which

Fig. 1 is an elevational view, in part section, of 30 an electric gaseous discharge device especially designed for use on direct current,

Fig. 2 is a similar view of a modification of the device of Fig. 1 which is intended for use on alternating current. 35

Fig. 3 is an elevational view, in part section, of a further modification of the device of Fig. 1, using a hot cathode.

Fig. 4 is an elevational view, in part section, of 40 a modification of the device of Fig. 3, and

Fig. 5 is a similar view of a modification of the device of Fig. 4 designed for use on alternating current.

In these drawings, with special reference to Fig. 1, there is shown an electric gaseous discharge device having a tubular envelope 1 of glass or other suitable vitreous material. At one end of said envelope 1 there is a cathode 2, of nickel or the like, which is preferably tubular in shape. Said cathode is supported by an inlead 3 which is 45 sealed through the end of said envelope 1. At the opposite end of said envelope there is an anode 4 of graphite, iron, or other suitable material which is supported by the inlead 5. A third electrode 6 forms a continuation of an inlead 7 50

- which is sealed through the cathode end of the envelope 1, and preferably consists of a wire of nickel, molybdenum, or the like of suitable rigidity, say of .30 mils diameter. Said electrode 6 passes through the cathode 2 and extends up the arc tube to a point within a few millimeters of the anode 4. A support 8 which is welded to the electrode 6 near the free end thereof serves to maintain the axial position of said electrode. Additional supports of like nature may also be used at intermediate points along the electrode 6 if desired, in which case said electrode may be of lighter construction. The inlead 5 is connected directly to the positive terminal of a suitable source of direct current, while the negative terminal of said source is connected through a ballast resistance 9 to the inlead 3 and to the inlead 7, the latter connection including a high resistance 10. The device of Fig. 2 has an envelope 1 which is similar to that of Fig. 1, and likewise has a tubular cathode 2, supported by an inlead 3, at one end thereof. An identical tubular cathode 12, supported by the inlead 13, is located at the opposite end of the envelope 1, however, replacing the anode of Fig. 1. A wire electrode 6, forming an extension of the inlead 7 likewise extends through the cathode 2, while a similar wire electrode 16, formed as an extension of the inlead 17, extends through the cathode 12, said electrodes 6 and 16 terminating with a short gap of the order of a centimeter therebetween at a point near the center of the envelope 1. Suitable supports 8 are provided to hold the free ends of each of the electrodes 6 and 16 in the desired position. The inlead 3 is connected to one terminal of a suitable source of alternating current through the ballast resistance 9, and the inlead 17 is connected to the same terminal through said resistance 9 and an added high resistance 10. Similarly the inlead 13 is connected directly to the other terminal of said source, while the inlead 7 is connected to the same terminal through the high resistance 10. In each of the devices of Figs. 1 and 2 the cathodes 2 and 12 and the wires 6 and 16 are preferably coated with a substance having a low work function, such as an alkaline metal or a compound thereof, in order to more efficiently use the applied potential. A surface having the desired characteristic is conveniently prepared by coating these parts with a compound such as barium azide, and then reducing this azide to pure barium by the use of heat after the device has been evacuated. The cathodes 2 and 12 are, of course, easily heated in the usual manner by an induction furnace to the temperature necessary to decompose the azide coating, but the wires 6 and 16 have so little mass that such heating thereof is difficult. I have discovered, however, that the gas evolved during the treatment of the cathodes is sufficient, even though the device be still connected to an exhaust system, to support an inductive discharge about the adjacent part of the wires 6 and 16 by which said wires are heated to the required temperature, the gas evolved during the reduction of the azide on this part of the wire being utilized to support a discharge on the adjoining part thereof, and so on; the induction coil or "furnace" being moved along the device at a pace which keeps up with the evolution of gas from the azide coating on the wire. This procedure leaves a coating of metallic barium on the surface of the cathodes 2 and 12 and of the wire electrodes 6 and 16, this

barium being intermixed with some nitride and a trace of unreduced azide which function to cement the barium to the surface of the electrode. The surface of these electrodes is then further improved by distilling metallic caesium or other alkali metal thereonto. This is conveniently done by heating the pellet 11, which contains a mixture of a caesium or other alkali metal compound and a reducing agent, such as a mixture of caesium dichromate and silicon. This heating obviously causes caesium vapor to be produced, some of this vapor condensing on the desired electrode surfaces. When so prepared these surfaces are found to have an extremely low work function, this characteristic being retained throughout a long useful life of a thousand hours or more. As an alternative to this coating process the electrodes and the wires may be coated with a mixture of barium and caesium azides, as disclosed in my Patent 1,965,588, granted July 10, 1934. According to the novel procedure there disclosed the barium azide is first broken up by heating to 180° C. following which the caesium azide is partly broken up by a gaseous discharge, producing a surface having an unusually long useful life.

The envelope 1 of the devices of both Fig. 1 and Fig. 2 is filled with a suitable gaseous atmosphere such as neon, helium, argon, nitrogen, mercury vapor or the like. These gases may be used alone or in combination with each other, as desired. For certain purpose, however, I prefer to use a combination of gases, such as proposed in my Patent 1,990,175, granted February 5, 1935, in which the principal gas is modified by a trace of another gas having an ionizing potential which is less than the meta-stable potential of the principal gas. For example, in a neon lamp I prefer to use a mixture of neon with about 0.2% of argon. In any case the pressure of the gas is a compromise between the low pressure at which the positive column is most efficient and the somewhat higher pressure at which a glow discharge is most easily produced. In practice I use a pressure of the order of 3-6 m. m. of mercury, although for special purposes somewhat higher or lower pressures may be used if desired.

The lamp shown in Fig. 3 has a tubular envelope 20 of glass or other suitable vitreous material. At one end of said envelope 20 there is an anode 21 of nickel, iron, tungsten, graphite or the like, which is supported by an inlead 22. This anode may be of any desired shape, but has been illustrated as cup-shaped, since in certain cases a lower anode fall results from the use of such an anode. At the opposite end of the envelope 20 there is a thermionic cathode 23 which preferably consists of a cellular electrode which closely surrounds a heater 24. Said cathode 23 is itself surrounded by the tubular heat conserving shields 25 and 26 to which it is electrically connected, the heat shield 26 preferably extending some distance beyond said cathode 23. Said heater 24 is designed for operation on 110 volts, hence the heating coil thereof (not shown) is completely embedded in a suitable refractory material, such as alundum, in order to prevent the formation of an arc between different portions thereof. One end of said heating coil is connected to an inlead 27, which is also shielded in a suitable manner to prevent the formation of an arc thereto, while the other end of said heating coil is electrically connected to the cathode 23. The inlead 28 is attached to the heat shield 25

26, and hence is electrically connected to the cathode 23. Said cathode 23 and the heat shields 25 and 26 are conveniently formed of nickel or the like. The inner surfaces of the cathode 23 are preferably coated with an alkaline or alkaline earth metal or compound thereof, in order to reduce the work function of these surfaces. For instance, I prefer to use a mixture of barium and strontium oxides, these oxides being conveniently reduced from the carbonates in situ by the use of heat in a well known manner. In some cases I also coat that portion of the inner surfaces of the heat shields 25 and 26 which extends beyond the cathode 23 with a material, such as powdered aluminum, which is known to resist activation by particles sputtered from the active cathode surface, in order to permanently confine the discharge to the desired surfaces within the cathode 23. A third inlead 29 which is sealed into the cathode end of the envelope 20 extends beyond the heat shield 26, the end thereof terminating in a ring 30 which is concentric with, and of about the same diameter as, the heat shield 26 and which lies in a plane close to the end of said shield. Said ring serves as an auxiliary anode, and hence is preferably made of nickel, iron, tungsten, or other suitable material. In order to confine the discharge to the ring 30 a vitreous sleeve 31 is preferably placed about that portion of said inlead 29 which extends alongside of the heat shield 26. A conductor 32 of suitable rigidity is attached, preferably by welding, to said inlead 29 at a point near the ring 30, said conductor extending up the arc tube to a point adjacent to the anode 4, the free end of said conductor being held in the desired position within the envelope 20 by a support 33. The inleads 22 and 27 are connected directly to the positive terminal of a suitable direct current source, while the inlead 29 is connected to the same terminal through a high resistance 34. The inlead 28 is in turn connected to the negative terminal of said source through the ballast resistance 35.

The conductor 32 is preferably coated with a substance having a low work function, such as barium, this coating being conveniently produced by the same method, set forth in detail hereinbefore, by which the coating is produced on the wires 6 and 16.

The device shown in Fig. 4 is in most respects identical with that shown in Fig. 3. The conductor 32' is, however, electrically isolated from the inlead 29, although it preferably extends to a point within a few millimeters thereof. Said conductor 32' is conveniently held in place by the ring support 36 and the support 37, to the latter of which it is welded, said supports being fused into the wall of the envelope 20. Said conductor 32' is coated with barium or the like in the same manner as the conductor 32 of Fig. 3. An alternate arrangement of the operating circuit is also shown in this figure, the ballast resistance 35 here being included in the positive lead, while the inlead 29 is connected through the high resistance 34 to a point between the resistance 35 and the inlead 22.

The device shown in Fig. 5 is identical with the device of Fig. 4, save that the anode 4 of Fig. 4 is replaced by a thermionic electrode assembly which is similar to the cathode assembly of Fig. 4. In this modified structure the inlead 22 is connected to one end of the heater 38, the other end of said heater being connected to the outer shield 39 about the thermionic cathode (not shown).

The heater 38 is furthermore so proportioned as to carry the main discharge current. The inlead 22 is connected to one terminal of a suitable alternating current source through a resistance 35', of less resistance than the resistance 35, it being understood, however, that in some cases, where the heat shield 39 has sufficient heat radiating capacity, this external ballast resistance 35' can be entirely omitted, the resistance of the heater 38 being correspondingly increased to 10 ballast the discharge. The inlead 29 is connected to the same terminal of the source through the high resistance 34, while the inlead 27 is also connected directly to the same terminal. The other terminal of said source is connected to the 15 inlead 28.

In each of the devices shown in Figs. 3-5 the envelopes 20 are filled with a suitable gaseous filling such as has been described in connection with the devices of Figs. 1 and 2. Due to the 20 greater facility with which the initial breakdown occurs with this type of device it is, however, possible to use somewhat lower pressures than are employed with the devices of Figs. 1 and 2, with a corresponding increase in luminous efficiency, 25 pressures of 2-4 m. m. of mercury being found especially effective where neon is employed, and even lower pressures, of the order of 1-3 m. m. of mercury being found suitable if a trace, of say .01 to 1% argon is added thereto, in accordance 30 with the principles outlined in Patent 1,990,175, previously referred to herein. Correspondingly, low pressures are preferably used where other gaseous fillings are employed.

In the use and operation of the device of Fig. 35 1 upon application thereto of a suitable direct current potential, say of 110 volts D. C., breakdown of the gas space occurs between the anode 4 and the adjacent end of the conductor 6 with a resultant glow discharge, this breakdown occurring at a relatively low potential, despite the low pressure of the gas, due to the low work function of the coating on said conductor. Due to the well known phenomenon that a glow discharge always tends to extend over such an area on the cathode 45 as to maintain a fixed current density (for any given gas pressure) at which the normal cathode fall is maintained, the glow discharge immediately extends down the length of the conductor 6 toward the cathode 2, the resistance 10, of the 50 order of 10,000 ohms, being so proportioned as to limit the current to substantially that value which will cause the glow to completely cover said conductor 6. This glow discharge, of course, causes a copious ionization of the gas about the 55 conductor 6 throughout the length of the arc tube with the result that a positive column discharge occurs virtually instantly between the cathode 2 and the anode 4, this latter discharge having the usual characteristics of an arc whose 60 current is limited to a desired value by the ballast resistance 9. Where a mixture of gases is employed, as disclosed in my co-pending application, Serial No. 541,021, which has been hereinbefore referred to, it is obvious that the radiations from 65 the glow discharge will be effective to produce ionization throughout the tube, greatly adding to the ionization which is obtained by diffusion alone where any of the pure gases are present. Thus where such gas mixtures are used it has been 70 found possible to make the positive column at least 25% longer, for a given voltage, than is possible with pure gases, positive column discharges of 10 to 12 tube diameters in length being started with ease on 110 volts D. C. where 75

the aforesaid neon-argon gas mixture is employed.

While I have described the device of Fig. 1 as being operated on direct current it is obvious that it can be operated on alternating current if so desired. In this case a positive column discharge will occur every alternate half cycle, this half-wave discharge being reinitiated once each cycle in the manner which has been described above, 10 as is readily apparent.

Upon application of a suitable alternating current potential to the device of Fig. 2 a glow discharge starts on each half cycle at three different points: between the ends of the conductors 15 6 and 16 between the electrode 2 and the conductor 6, and between the electrode 12 and the conductor 16. Assuming that at a given moment the electrode 2 is negative with respect to the electrode 12, it is obvious that a cathode glow 20 will cover said electrode 2, and that the glow discharges at each end of the conductor 16 will spread along the entire length of said conductor, so that there is a cathode glow discharge, accompanied by ionization of the gas, throughout 25 an appreciable portion of the gas column between the electrodes 2 and 12. This ionization, together with the resulting diffusion thereof up the tube is sufficient in some cases to permit the immediate initiation of the main positive column 30 discharge from the acting anode 12 to the acting cathode 2 at the normal applied potential. Where especially long tubes, of the order of 20 tube diameters in length, are operated on 110 volts the starting of the main discharge is sometimes delayed, however, until the next half cycle. 35 The electrode 12 is then covered with a cathode glow, as is the entire conductor 6, with a resulting ionization of the gas thereabout. In case the main discharge was initiated on the first half cycle, it is obvious that it will be immediately reinitiated in the reverse direction as a result of this ionization in the same manner described above. Where the discharge is not initiated during the first half cycle, however, there is considerable ionization still remaining about the conductor 16 after the potential has reversed, this residual ionization cooperating with the positive ions which diffuse into that portion of the tube to permit the initiation of the main discharge 40 from the acting anode 2 to the acting cathode 12. The reinitiation of the discharge on each successive cycle thereafter is, of course, obvious.

Where mixtures of gas, such as the neon-argon mixture hereinbefore mentioned, are used even 55 longer positive column discharges, of the order of 24 tube diameters in length, may be readily initiated on 110 volts A. C. In this case the radiations from each of the glow discharges pass up the tube exciting atoms of the main gas, many of these excited atoms passing into a metastable level as a result of collisions. Upon collision of any of these metastable atoms with an atom of a gas of lower ionizing potential the energy is transferred, with a resulting ionization of the gas. 60 The ionization thus produced throughout the tube, added to the ionization directly produced by the glow discharges, greatly facilitates the initiation of the main discharge and permits even longer positive column discharges to be initiated 65 on a given voltage than would otherwise be possible.

In the operation of the device of Fig. 3, upon energization of the leads thereto with direct current of suitable potential, say 110 volts D. C., the 70 cathode heater 24 is immediately energized and

begins to heat the cathode 23. Line potential is impressed during this period between the auxiliary anode 30 and the cathode 23, but the spacing therebetween is preferably made large enough that there will be no appreciable discharge therebetween until the cathode 23 has been heated to its normal operating temperature. In this way premature initiation of the main arc discharge, before the free electron emission from the cathode 23 is sufficient to support the normal discharge 10 current without the formation of destructive localized hot spots on said cathode, is avoided. As the temperature of the cathode rises the electron emission therefrom rapidly increases, altering the potential distribution between said cathode and 15 the auxiliary anode 30 to such an extent that eventually the gas therebetween is sufficiently ionized to permit an arc discharge therethrough at line potential. As soon as this occurs the potential of the auxiliary anode 30 is lowered by 20 the resistance drop in the resistance 34 to substantially space potential. Where this auxiliary electrode is made relatively large, as is preferred, so that the random current which could be collected thereby, if it were not for the resistance 25 34, is greater than the current actually collected thereby, there is a negative anode fall, as is well known, with the result that said auxiliary anode operates at a potential somewhat less than that of the surrounding space. For example, in a 30 neon lamp the space potential about said anode is about 21 volts, while the negative anode fall is easily made of the order of 5 or 6 volts, with the result that said auxiliary anode operates at a potential of the order of 15 volts above that 35 of the cathode. This low potential of the auxiliary anode 30 is highly important, since the lower the potential thereof the greater is the potential difference available to initiate a glow discharge between the anode 21 and the wire 32 40 as a cathode as the next step in the initiation of the main discharge. Where the potential of the auxiliary anode 30 is thus 15 volts, 95 volts is obviously impressed between said anode 21 and the wire 32, where the line potential is 110 volts. Due 45 to the low work function of the coating on the surface of said wire 32 this potential is adequate to initiate a glow discharge therebetween, this glow discharge rapidly spreading down said wire toward the cathode 23, and thus ionizing the gas 50 throughout the length of the tube. As a result of this ionization the main positive column discharge, of the order of 18 tube diameters in length, is immediately formed between the main anode 21 and the cathode 23, and continues so long as 55 potential is applied to the device.

In the case of pure gases the initiation of the aforesaid cathode glow discharge to the wire 32 is facilitated by the radiations from the discharge between the auxiliary anode 30 and the cathode 60 23. These radiations reach the end portion of the wire 32 and as a result of their photo-electric effect thereon cause a certain amount of electron emission therefrom, and thus permit the initiation of the desired glow discharge at a potential 65 lower than would otherwise be possible. As a result my novel device readily functions on 110 volt direct current lines despite appreciable voltage fluctuations therein. By the addition of a trace of another gas, such as argon where the 70 main gas is neon, having an ionizing potential slightly less than a metastable potential of the main gas, as disclosed in my copending application, previously referred to, the radiations from the auxiliary discharge to the hot cathode 23 75

also produce an appreciable amount of ionization throughout the length of the tube, further facilitating the initiation of the cathode glow discharge to the wire 32, and then cooperating with said glow discharge to produce the necessary ionization for the initiation of the main positive column discharge. Thus even longer positive column discharges may be initiated on 110 volts D. C. with such a mixture of gases than is possible with the use of a pure gas alone in my novel lamp. Due to the inclusion of the ballast resistance 35 in the cathode lead the voltage on the heater 24 is reduced as soon as the main discharge is initiated, thus reducing the energy input thereto.

While the various steps in the starting of the discharge in this device have been described as taking place sequentially it is to be understood that once the cathode 28 has reached such a temperature that the discharge from the auxiliary anode 30 is initiated the remaining phenomena take place virtually instantly, there being no perceptible time lag. As a result this device may be satisfactorily operated with a half-wave discharge on alternating current, if desired. In this case somewhat longer positive column discharges can be readily initiated on 110 volts, due to the greater peak voltage available.

The operation of the device of Fig. 4 is in many respects similar to that of the device of Fig. 3. Upon application of a suitable potential, such as 110 volts D. C., the cathode 28 is heated in the same manner, with a resultant discharge thereto from the auxiliary anode 30 as soon as the thermionic emission therefrom has reached the desired value. This discharge ionizes the gas in the immediate vicinity thereof, creating a plasma whose space potential, in neon, is of the order of 21.5 volts above that of the cathode. The end of the wire 32' projects into this plasma, and has been found to assume a potential less than that of space of the order of 4 times the average energy, in volts, of the random electrons in the gas. Thus in neon the end of this wire has a potential of from 3-7 volts less than that of the surrounding space, or 14.5-18.5 volts above that of the cathode 28. Due to the fact that the wire 32' is a good conductor the entire wire assumes this potential, so that in a 110 volt lamp from 90-95 volts is impressed on the gap between said wire and the anode 21. This potential causes the formation of a cathode glow discharge therebetween, this discharge extending down said wire 32' and ionizing the gas throughout the length of the tube, permitting the main discharge to be initiated by the line potential in the same manner as in the device of Fig. 3. From the foregoing it is obvious that it is desirable that the wire 32' should float at as low a potential as is consistent with the collection of enough electrons from the cathode 28 to support the glow discharge.

Upon applying a suitable alternating current potential to the device of Fig. 5 a half-wave discharge is initiated therein on every half cycle that the cathode 28 is negative in exactly the same manner that the discharge is initiated in the device of Fig. 4, as described above. The discharge current passes through the heater 38, heating the associated electrode assembly, and there is also some anodic heating thereof. As a result the oxide coated portion of this assembly soon freely emits electrons whenever it is negative, permitting the initiation at line potential of the main discharge in the reverse direction through the gas column, which retains some ionization from the previous half cycle. Thus

this device starts with a half-wave discharge and then changes over to a full-wave discharge device after the second thermionic electrode has been heated to the requisite temperature.

A mixture of gases, such as the neon-argon mixture hereinbefore mentioned may obviously be used in either the device of Fig. 4 or that of Fig. 5 with beneficial results, such as increase in the maximum length of discharge which can be initiated with a given voltage. The operation of the device in such a case is obvious from the foregoing description and hence will not be further described.

While I have described my invention by reference to specific embodiments thereof, it is to be understood that it is not limited thereto, but that various changes, substitutions, or omissions, within the scope of the appended claims, may be made therein without departing from the spirit thereof.

I claim as my invention:

1. An electric gaseous discharge device comprising a tubular sealed vitreous envelope containing a gaseous atmosphere, an electrode sealed into said envelope at each end thereof, a conducting wire extending within said envelope from a point near one of said electrodes toward the other of said electrodes, said wire being coated with an alkaline metal, and means to electrically connect said wire to a single one of said electrodes, whereby substantially all of a potential which is impressed between said electrodes is concentrated over a short path to initiate a discharge in said device.

2. An electric gaseous discharge device comprising a tubular sealed vitreous envelope containing a gaseous atmosphere, an electrode sealed into said envelope at each end thereof, and a conducting wire extending within said envelope from a point near one of said electrodes toward the other of said electrodes, said wire being coated with an alkaline metal and connected to one of said electrodes through a resistance which is isolated from the path of a discharge between said electrodes.

3. An electric gaseous discharge device comprising a tubular sealed envelope, a main electrode at one end of said envelope, said electrode being adapted to emit electrons when heated, means to heat said electrode, an auxiliary anode adjacent to said main electrode, another main electrode at the opposite end of said envelope, and an electrical conductor extending within said envelope from a point near said last mentioned electrode to a point near said auxiliary anode.

4. An electric gaseous discharge device comprising a tubular sealed envelope, a main electrode at one end of said envelope, said electrode being adapted to emit electrons when heated, means to heat said electrode, an auxiliary anode adjacent to said main electrode, another main electrode at the opposite end of said envelope, and an electrical conductor extending within said envelope from a point near said last mentioned electrode to said auxiliary anode, said conductor being electrically connected to said anode.

5. The method of producing a coating of low work function on an electrode which comprises coating said electrode with an alkaline compound which decomposes with the evolution of gas when heated, sealing said electrode into an envelope, evacuating said envelope, heating a portion of said electrode to a temperature sufficient to decompose said compound, and then producing an inductive discharge in the gas as evolved to heat

more of said electrode to a temperature sufficient to decompose said compound.

6. An electric gaseous discharge device comprising a tubular sealed envelope containing a gaseous atmosphere, an electrode sealed into said envelope at each end thereof, a conducting wire extending within said envelope from a point near one of said electrodes to a point near the other thereof, said wire being connected to a single 10 one of said electrodes through a resistance which is isolated from the path of a discharge between said electrodes.

7. An electric gaseous discharge device comprising a tubular sealed envelope containing a gaseous atmosphere, a thermionic cathode at one end of said envelope, an auxiliary anode adjacent to said cathode, another electrode at the opposite end of said envelope, and an electrical conductor extending within said envelope from a point near the latter electrode to a point sufficiently near said auxiliary anode to be in the plasma of a discharge between said auxiliary anode and said cathode. 5

TED E. FOULKE.
